UNITED STATES PATENT OFFICE.

JOHN BURKHARDT, OF NEW YORK, N. Y.

CASTING-MACHINE.

1,108,693.

Specification of Letters Patent. Patented Aug. 25, 1914.

Application filed December 17, 1910. Serial No. 597,744.

To all whom it may concern:

Be it known that I, JOHN BURKHARDT, a citizen of the United States, and a resident of the city, county, and State of New York, have invented certain new and useful Improvements in Casting-Machines, of which the following is a specification.

My invention relates to casting machines.

It has for its object to provide a machine which will automatically, quickly and cheaply cast articles of any desired shapes or sizes or of varying or irregular shapes or which will be adapted to cast a great variety of different articles at the same time; also to provide means for more easily separating or breaking up the finished casting into its constituent cast parts; and also means for reducing the waste and for making portions of waste into useful articles.

In the accompanying drawings, forming part of this specification, I have shown my improvement in its preferred form.

Referring to this embodiment of my invention Figure 1 is a side elevation of such form of my improved device. Fig. 2 is a plan. Fig. 3 is a vertical section taken between the chains showing in elevation one series of the movable mold blocks with the funnels, gate-ways and other parts. Fig. 4 is a horizontal section taken on the lines 4—4 of Fig. 1. Fig. 5 is a detail of the delivery of a cast article. Figs. 6, 7 and 8 illustrate an elevation of my improvement in which movable plungers are employed to occupy part of the molding space during the casting operation, Fig. 6 showing a vertical cross-section through the chains and other parts of the upper part of the apparatus, Fig. 7 being a horizontal section on the lines 7—7 of Fig. 6, and Fig. 8 being a detail of the plunger and its cam. Figs. 9, 10 and 11 illustrate another modification for preventing waste or for making use of the waste parts of the castings, Fig. 9 being a vertical elevation showing the gate-way, funnel and the face of one series of molding blocks, Fig. 10 being a top view of the mold of Fig. 9, omitting certain parts, and Fig. 11 being a vertical cross-section. Figs. 12 and 13 are details of a modification.

In my improvement I provide a plurality of series of movable mold blocks adapted to be brought together to form molding spaces of any desired shape and size, provided with

suitable gate-ways for leading the metal to the molding spaces and adapted to be separated to discharge the cast articles. The mold blocks may be of any suitable shape or construction and may be connected together in any suitable manner. In the machine shown in the drawings they consist of endless chains provided with mold link blocks. The mold blocks 1, 1 are fastened to links 2 forming an endless chain 3. I have shown two of these endless chains 3 in the drawings. Each is constructed in the usual manner of a sprocket chain and is supported or carried by four sprocket wheels 4—4, two carried on upper axles 5 and the other two on lower axles 6. The mold blocks 1—1 are fastened to the links 2, 2 of the endless chains in any suitable manner and the links are secured together in the usual manner, so as to engage the teeth of the sprocket wheels 4—4. Each molding block extends across the whole width of the chain from one sprocket wheel to another as shown in Fig. 2. The various mold blocks are provided with any suitable shaped spaces and these spaces form one half or part of complete molding spaces, the other part being of course supplied by the opposite molding blocks. These molding spaces may be of any desired shape or size and may be of varying or irregular shape as illustrated in Fig. 3, where are shown a number of different molding spaces 7 of different and irregular shapes and sizes adapted to make different articles.

Suitable gate-ways are provided for supplying metal to the molding spaces. In practice I prefer to use main gate-ways and subgate-ways for leading the metal to the various molding spaces, and in practice I prefer to use two main gate-ways with subgate-ways leading from each, as shown in Fig. 3.

8—8 are two funnels for supplying metal, each leading to a main gate-way 9. Each gate-way 9 is provided with subgate-ways 10 leading to the various molding spaces 7. It will of course be understood that as the opposing mold blocks of the two opposite series of chains 3 are brought together, as the chains are moved by the sprocket wheels (in the direction of the arrows shown in Fig. 1), as illustrated near the top of Fig. 1, the various molding spaces 7, the main

gate-ways 9 and subgate-ways 10 will be completed and the metal will pour down from the funnels through the main gate-ways and subgate-ways and fill the molding spaces, and as the molding blocks separate, as shown at the bottom of Fig. 1, the cast articles together with the waste matter in the gate-ways will be discharged, as illustrated in Fig. 5. There a cast article 11 is shown in the act of dropping out.

By means of my improvement articles of different shape and size and of any irregular shape and size may be cast and a great variety of articles may be cast at the same time.

By my improvement I am enabled to provide numerous sub-gate-ways, preferably two or more for each molding space. This enables the molding space to be quickly and readily filled. For this purpose also I prefer to employ two or more main gate-ways each provided with its own funnel, as shown in Fig. 3. By proper sub-gate-ways these main gate-ways coöperate with one another.

The chains may be driven by any suitable means. Those shown consist of sprocket wheels 12 and 13 meshing with each other and affording motion from one chain to the other chain. A shaft 5 upon which gear 13 is mounted may be driven from any source of power (not shown).

For the purpose of making articles of a different and larger size or irregular shape it is sometimes preferable to construct a main gate-way so that it could shift in its course relatively to the line of movement of the chains or blocks instead of being always parallel. Thus while the gateway 9 at the right of Fig. 3 is shown as vertical, or in other words is parallel to the line of movement of the chains, the left hand main gate-way 9 is shown as shifting relatively to the line of movement of the chains at different times. Thus in the upper part of Fig. 3 the main gate-way 9 is to the left as it is at the bottom, but at the intermediate points it is shifted to the right. This is to enable the placing of the large rectangular space 7 shown inside the curve of the main gate-way as appearing on Fig. 3. It is, of course, necessary with a shifting main gate-way to also shift the horizontal position of its funnel 8. Accordingly the left hand funnel 8 is shown as a movable one adapted to shift its position horizontally or across the machine, as viewed in Fig. 3, to correspond with the shifting of the main gateway. Any suitable means may be employed for shifting the funnel. Those which I employ are as follows: The left-hand funnel 8 is carried or supported by two rings 15, 16 having collars 17 and 18 respectively. Collars 17, for it will be understood that there is one on each side of ring 15, loosely encircle a cross rod 19 fixed in side supports 20

and 21 of the machine. To this same rod 19 the right hand funnel 8 is secured by a ring 22 and a collar 23 is fastened to the ring and to the rod. Collar 18 of ring 16 of the movable or left hand funnel 8 is made fast by a collar 24 to a shifting rod 25 mounted in cylindrical openings in the supports 20 and 21 and free to move horizontally in them. It will be understood that there are two rods 19, one on each side of the funnel and but one rod 25. Spring 26 is secured at one end to ring 16 and at the other end to support 21. It tends to pull the movable or left hand funnel 8 to the left as viewed in Fig. 3. The funnel is pulled to the right by means of cam surfaces 27 projecting from the right hand end of certain of the blocks 1, as shown in Fig. 3. An arm 28 encircles and is fast at its upper end 29 to rod 25 and at its lower end has a wheel 30 pressing against the right ends of the blocks 1. The cams are shaped and proportioned of course so as to move the funnel 8 to the right or permit it to be pulled by spring 26 to the left so as to conform with the shifting of its main gate-way 9.

In Figs. 6-8 I have shown a plunger adapted to be moved into an occupied part of a molding space during the casting operation of the blocks, with suitable cams for moving it into and out of operation. This enables the shape of a molding space to be altered to suit circumstances and permits of the use of larger molding spaces.

The plungers may be of any desired size and shape and may be moved into and out of position in the molding space by any suitable means. As shown in Figs. 6-8 31 are plungers adapted to be moved into the molding spaces 7 by means of arms 32 provided at their ends with wheels 33 running in cam grooves 34. These cam grooves are shaped so as to insert the plunger and withdraw it at the proper times. Fig. 6 shows the upper plunger 31 in position in its molding space and shows the lower plunger 31 withdrawn from its molding space. By these means castings of a greater variety of shape may be made than would be otherwise possible, and castings with recesses on any or every side.

In order to obviate as much as possible the waste of metal on account of the main and sub-gate-ways I preferably provide means for forming the metal remaining in the main gate-way or gate-ways at the time of delivery into useful articles. In Figs. 9-11 I have illustrated my preferred devices for this purpose. As there shown I provide in the center of the main gate-way 9 and projecting upward through the center of funnel 8 a core 35 which may be of sand or any material suitable for that purpose. For this purpose I provide the funnel 8 with

an inner cylindrical sleeve 36 at its upper part to form a guide for the core. 37-37 are properly shaped wheels suitably supported (supports not shown) for also guiding the core. 38-38 are knobs or projections from the opposing faces of the molding-blocks 1 to act as guides for the core. Such knobs are provided at suitable distances apart, only one set of them being shown in Fig. 11. In this way the metal filling the gate-way 9 is formed into a useful article, namely, a pipe instead of being merely waste material that would have to be melted and used over again.

13 By making the knobs or projections 38 continuous so as to form a complete circle around core 35, the pipe will be divided into sections of certain prescribed lengths or if the projections do not quite touch the core 20 there will be restricted parts which can be easily broken through. Similarly I prefer at certain prescribed distances apart to restrict the main gate-ways 9-9, even where a core is not used, by an inner circular projection upon the blocks in order to provide that the casting will be thinner at such points and can be more readily broken. In Fig. 3 I have illustrated such a restriction at 39 and in Fig. 12 I have shown such a 25 continuous ring or circular projection and in Fig. 13 I have shown a portion of the waste from main gate-way 9 after delivery having such restricted portion 40.

41-41, secured to brackets 44 fastened to 35 the side frames of the machine, act as guides for projections 42-42 extending from the edges of the molding blocks, thus keeping the molding blocks in proper alinement and position.

40 43 is a backing of asbestos which I preferably employ on the mold-blocks for conserving heat.

The term "metal" as used in the specification and claims is used broadly to indicate any suitable metallic or other substance in fluid or in semi-fluid condition at the time of casting and adapted to set and adapted for use in a casting machine. My invention is, however, peculiarly applicable 45 to making castings from molten iron although not limited to this material.

In the machine shown the line of movement of the molding-blocks and the line of the main gate-ways are in the main in a 55 vertical direction, gravitation being relied upon to cause the metal to flow through the gate-ways and into the molding spaces. It will be understood however that with any other suitable means or method for forcing 60 the metal into such spaces in a direction other than vertical, the line of movement of the molding blocks and the line of the main gate-ways need not be vertical.

Many changes and modifications in or 65 from the particular form of mechanism

shown in the drawings and many departures therefrom may be made without departing from my invention.

It will, of course, be understood that in first beginning operations with my improved casting machine, it will be necessary to temporarily plug up the bottom of each main gateway until the gateway and the sub-gateways and molding spaces above it have been filled. This can be done by any suitable temporary plug. After the machine has once been in operation and is stopped at the close of the day or for any reason, the place of the temporary plug can be filled by leaving the machine so that a casting is only partly discharged, such as the position of the casting 11 shown in Fig. 5. This will act as a plug until the machine is started again. Upon starting the machine, either in the first or any subsequent operation, the temporary plug or the casting 11 will be discharged in the usual way.

In practice, I prefer to so arrange the molding spaces and the gateways and sub-gateways so that the cubical contents of them all will be approximately the same in any given unit of length of the molds, in order to obtain as even a flow of metal as possible. This will tend to obviate any overflow of metal at any particular time. Should such an overflow, however, occur for any reason, it may be provided for in any suitable way, as for example, by means of extra or additional passageways. As these form no part of the present invention, they are not herein shown and described.

What I claim as new and desire to secure by Letters Patent is—

1. The combination of a plurality of series of movable mold-blocks adapted to be brought together to form a plurality of molding spaces of any desired sizes and shapes, a plurality of main gate-ways for the passage of the metal, and a plurality of sub-gate-ways for leading the metal from the main gate-ways to the molding spaces, the different series of mold-blocks adapted to be separated to discharge the cast articles, and a funnel for each main gate-way for supplying metal thereto.

2. The combination of a plurality of chains provided with mold link-blocks adapted to be brought and moved together to form a plurality of molding spaces of any desired sizes and shapes, a main gate-way for the passage of the metal shifting in its course from the line of movement of the chains, and sub-gate-ways for leading the metal from the main gate-way to the molding spaces, the chains and mold link-blocks adapted in their further movement to be separated to discharge the cast articles.

3. The combination of a plurality of chains provided with mold link-blocks adapted to be brought and moved together

to form a plurality of molding spaces of any desired sizes and shapes, a main gate-way for the passage of the metal shifting in its course from the line of movement of the chains, and sub-gate-ways for leading the metal from the main gate-way to the molding spaces, the chains and mold link-blocks adapted in their further movement to be separated to discharge the cast articles, and 10 a movable funnel for supplying metal to the main gate-way adapted to shift its position to correspond with the shifting of the main gate-way.

4. The combination of a plurality of 15 chains provided with mold link-blocks adapted to be brought and moved together to form a plurality of molding spaces of any desired sizes and shapes, a plurality of main gate-ways for the passage of the metal, one 20 or more of said gate-ways shifting in its course from the line of movement of the chains, a plurality of sub-gate-ways for leading the metal from the main gate-ways to the molding spaces, the chains and mold 25 link-blocks adapted in their further movement to be separated to discharge the cast articles, a funnel for each main gate-way for supplying metal thereto and means for shifting the position of a funnel to correspond with the shifting of its gate-way.

5. In a molding machine the combination with a plurality of series of movable mold-blocks adapted to be brought together to cause the corresponding mold-blocks in the 35 different series to form between them a hollow space adapted to constitute a molding space and to be separated to discharge the cast article, of a plunger of desired size and shape adapted to be moved into and to occupy part of the molding space during the casting operation and to be withdrawn at or prior to the separation of the blocks.

6. In a molding machine the combination with a plurality of series of movable mold-blocks adapted to be brought together to cause the corresponding mold-blocks in the 45 different series to form between them a hollow space adapted to constitute a molding space and to be separated to discharge the cast article, of a plunger of desired size and shape adapted to be moved into and to occupy part of the molding space during the casting operation and to be withdrawn at or prior to the separation of the blocks, and 55 a cam for moving the plunger into and out of position in the molding space at appropriate times.

7. The combination of a plurality of series 60 of movable mold-blocks adapted to be brought together to cause the corresponding mold-blocks in the different series to form between them hollow spaces adapted to constitute a molding space and a gate-way for leading the metal to the molding space 65 provided with a restricted portion to en-

able the said gate-way portion of the casting, when removed, to be more readily broken.

8. The combination of a plurality of series 70 of movable mold-blocks adapted to be brought together to cause the corresponding mold-blocks in the different series to form, between them hollow spaces adapted to constitute a molding space, a main gate-way for the passage of the metal provided with a 75 restricted portion to enable the said gate-way portion of the casting, when removed, to be more readily broken, and a sub-gate-way for leading the metal from the main gate-way to the molding space, the different 80 series of mold-blocks adapted to be separated to discharge the cast articles.

9. The combination of a plurality of series 85 of movable mold-blocks adapted to be brought together to form a molding space and a gate-way for leading the metal to the molding space, and a core for the gate-way adapted to form the metal finally remaining in the gate-way into a useful article.

10. The combination of a plurality of series 90 of movable mold-blocks adapted to be brought together to form a plurality of molding spaces of any desired sizes and shapes and a gate-way for leading the metal to each molding space, the different series 95 of mold-blocks adapted to be separated to discharge the cast articles, and a core for the main gate-way adapted to form the metal finally remaining in the gate-way into a useful article.

100 11. The combination of a plurality of series of movable mold-blocks, adapted to be brought together to form molding spaces and to be separated to discharge molded or cast articles, provided with molding spaces 105 for different shaped articles, a main gate-way for the passage of the metal shifting in its course from the line of movement of the mold-blocks, and sub-gate-ways for leading the metal from the main gate-way to the 110 molding spaces.

115 12. The combination of a plurality of series of movable mold-blocks, adapted to be brought together to form molding spaces and to be separated to discharge molded or cast articles, provided with molding spaces 120 for different shaped articles, a main-gate-way for the passage of the metal shifting in its course from the line of movement of the mold-blocks, and sub-gate-ways for leading the metal from the main gate-way to the molding spaces, and a movable funnel for supplying metal to the shifting main gate-way adapted to shift its position to correspond with the shifting position of the gate-way.

125 13. In a molding machine, the combination of a plurality of series of movable mold-blocks adapted to be brought together to form a gate-way, the molds being so shaped 130

and arranged as to cause the gate-way to shift its position in the molds, and a funnel adapted to shift or move with the shifting gate-way so as to be in position to furnish metal to the gate-way irrespective of its position in the molds.

In testimony whereof, I have signed my

name to this specification, in the presence of two subscribing witnesses.

JOHN BURKHARDT.

Witnesses:

EDWIN SEGER,

JOHN O. GEMPLER.
